UNITED STATES PATENT OFFICE

PER GUNNAR PALMGREN, OF GOTTFENBORG, SWEDEN, ASSIGNOR TO AKTIEBOLAGET SVENSKA KULLAGERFABRIKEN, OF GOTTFENBORG, SWEDEN, A CORPORATION OF SWEDEN

ROLLING MILL GUIDE

Application filed October 17, 1929, Serial No. 400,209, and in Sweden October 23, 1928.

In many cases it is usual to provide a guide before the rolls in rolling mills in order to guide the material to the pass and to prevent it from twisting in the pass.

5 The present invention is for the purpose of avoiding the disadvantages experienced with guides now in use and consists mainly of an arrangement by which the guide is kept open to allow the material to enter and 10 is automatically closed after the material has been gripped by the rolls. By this means the entrance of the material into the guide is greatly facilitated, while a satisfactory guidance is obtained. This guide may 15 be operated mechanically. The impulse required to make the closing mechanism function is obtained by the working load on the rolls.

This present application is closely related 20 to another application which I am filing concurrently herewith, this present application relating particularly to a design whereby the variation in load on the rolls of the rolling mill is utilized for actuating the 25 guides.

The accompanying drawings show a preferred form of an embodiment of the invention, in which drawings

Figure 1 shows an axial section through a 30 guide, the rolls being shown in cross-section, and

Fig. 2 shows a cross-section through the same guide.

A pair of work rolls 15 and 16 are illustrated 35 between which is to be passed the bar 14 for the purpose of reducing it. The purpose of the invention is to guide the oncoming portion of the bar as it is passing between the rolls.

40 The guide is represented as comprising two halves denoted by the numerals 1 and 2 which are carried by bell crank levers 32—33 rotatable about a fixed pivot 34. The bell crank levers are connected to links 37 45 and 38 by means of joints 35 and 36. The links 37 and 38 are connected to a bar 41 through a joint 39. The bar 41 is fixed in a transverse beam 40 resting on the bearing 50 housings 42 and 43 of the upper roll 15. When the material enters the pass the upper

roll and its bearing housings are raised. The joint 39 is thus lifted and since the pivot 34 is fixed the distance between these points is increased. This causes the bell-crank levers 32—33 to turn about the pivot 55 34 thus closing the guide. When the material has passed through, the upper roll falls back into its original position taking with it the bearing housings and the beam 40. Points 34 and 39 approach each other 60 and the guide is opened.

Having described my invention I claim and desire to secure by Letters Patent:

1. The combination with a mill provided with rolls, of guides for the material adapted to open the close, and an element connected to and following the up and down movement of the rolls as the material enters or leaves the pass for closing and opening the guides.

2. The combination with a mill having a frame and provided with rolls and bearings supporting such rolls, of guides for the material adapted to open and close, and means associated with the bearings and adapted to follow the up and down movement of one of the rolls as the material enters or leaves the pass for closing and opening the guides.

In testimony whereof I have signed my name.

PER GUNNAR PALMGREN.
